UNITED STATES PATENT OFFICE.

CHARLES E. VAN DEVENTER, OF SPRINGFIELD, ILLINOIS.

APPARATUS FOR AERIAL NAVIGATION.

SPECIFICATION forming part of Letters Patent No. 741,568, dated October 13, 1903.

Application filed July 5, 1902. Serial No. 114,455. (No model.)

To all whom it may concern:

Be it known that I, CHARLES E. VAN DEVENTER, a citizen of the United States, residing at Springfield, in the county of Sangamon and State of Illinois, have invented certain new and useful Improvements in Apparatus for Aerial Navigation, of which the following is such a full, clear, and exact description as will enable others skilled in the art to which it appertains to make and use my said invention.

My invention relates to apparatus for aerial navigation of that type which employ oscillating wings for lifting the apparatus and rotary propellers for propelling and guiding the apparatus.

The purposes of my invention are to provide a frame of novel and improved construction combining lightness with strength and rigidity, to provide lifting devices of novel and improved construction, to provide simple and effective means for operating the lifting devices and the propelling devices, to provide wings of novel and improved construction, to provide simple and effective means for initial spreading of the wings, to provide means to prevent undue spreading of the wings, to provide simple and effective means for steadyng the movement of the apparatus, and to provide means to prevent jar and injury to the apparatus during the operation of landing.

With these ends in view my invention consists of the novel features of construction and combinations of parts shown in the annexed drawings, to which reference is hereby made, and hereinafter particularly described and finally recited in the claims.

Referring to the drawings, Figure 1 is a side elevation of the complete apparatus. Fig. 2 is a horizontal section on the line 2 2 of Fig. 1. Fig. 3 is an enlarged partial vertical section through one of the wing-frames and one of the brace-frames on the line 3 3 of Fig. 2. Fig. 4 is an enlarged top plan of one section of one of the wing-frames and shows one pair of the wings mounted in that section of the wing-frame. Fig. 5 is a vertical longitudinal section on the line 5 5 of Fig. 4. Fig. 6 is an enlarged vertical transverse section on the line 6 6 of Fig. 4. Fig. 7 is a hori-

zontal transverse section on the line 7 7 of Fig. 1, the cranks being shown at approximately one quarter-turn from the position shown in Fig. 1 in order to more clearly illustrate the arrangement of the mechanism. Fig. 8 is an enlarged top plan of the propeller-driving mechanism, the top of the inclosing box being removed, so as to expose the mechanism within the box. Fig. 9 is a vertical longitudinal section on the line 9 9 of Fig. 8. Fig. 10 is a vertical transverse section on the line 10 10 of Fig. 8.

Similar reference - letters designate like parts in the several views of the drawings.

My apparatus may be connected with and supported on a balloon or other suitable gas-field by any suitable means. A balloon or other gas - field and means for connecting therewith lifting, propelling, and steering devices being well known in the art, I do not herein make any claim thereto, and it is therefore unnecessary to show and particularly describe said gas-field and connecting devices.

The essential features of my apparatus are a main structure provided with centrally-guided and oppositely - reciprocating wing-frames carrying wings which remain spread during the descent of the wing-frames and which fold, so as not to impede the ascent of the wing-frames, the apparatus being so constructed and arranged that when the wings on either of the wing-frames are spread that wing-frame and its wings will form an approximately cone-shaped aeroplane of area sufficient to materially contribute to the support of the structure, and when said aeroplane is moved downward by the operating engine or motor the aeroplane will act against the underlying column of air, compressing and displacing it to a degree, and thereby causing it to buoy the apparatus upward to an extent proportional to the weight of air displaced.

My invention also involves details of construction whereby I attain great strength and rigidity of the apparatus without unduly increasing its weight.

In its preferable form the main structure consists of four stationary circular frames A, suitably secured to vertical posts A' and hav-

ing hubs a , which are secured to a central vertical mast A^2 . The wing-frames B are circular and have elongated hubs B' , which are slideable on the mast A^2 . The hubs B' of the wing-frames and the guides D' are provided with ball-bearings, as shown, to facilitate the movement of the hubs on the mast and the movement of the guides on the posts A' . The rims of the frames A and B are for the sake 10 of lightness and strength made of thin steel tubes and having substantially the elliptical cross-sectional form shown in Fig. 3, and the rim of each frame is connected with its hub by spokes $a' b'$ of light and spring steel wire. 15 Midway between the rim and the hub of the frame B and concentric therewith is a circular middle brace D , to which the spokes b' are secured. The spokes b' have their inner ends secured to the hub B' and their outer 20 ends secured to the rims of the frame B in such manner that the spokes and their stays form a series of trusses supporting and strengthening the rims of the wing-frame and particularly adapted to prevent vertical dis- 25 placement of the rims of the frame. (See Fig. 5.) Guides D' , secured to the brace D , are slideable on the posts A' and guide the reciprocating movement of the wing-frames. Cross-pieces D^2 connect the guides D' . Wings 30 B^2 are mounted in pairs on the wing-frames B . Radial partitions B^3 divide the wing-frames into sections, and one pair of wings is mounted in each section. Stays b^2 , preferably of light piano-wire, stay the upper spokes 35 to the hubs and also stay the upper spokes to the lower spokes, thus stiffening and strengthening the wing-frame.

A wing-support consisting of a light metal tube or rod b^3 is situated above and parallel 40 to each of the spokes b' and passes through and is supported on intermedial vertical standards b^4 , secured on the spokes b' and having eyes through which the rod b^3 passes. The inner ends of the wing-supports b^3 screw 45 into the hub B' , and their outer ends are supported on blocks b^5 , secured on top of the rim of the wing-frame B . The wings B^2 are pivotally connected with the rods b^3 , and the rods are removable for convenience in mount- 50 ing and dismounting the wings. The wings consist of wire skeletons covered with silk or other light and strong fabric. (See Fig. 4.) Each wing-skeleton consists of suitable number of longitudinal wires or tubes b^4 of suffi- 55 cient strength and connected together by transverse wires or tubes b^5 . At the free end of each of the members b^5 is an eye through which the rod b^3 passes. In each wing there is a lateral slot b^6 , which permits the wing to 60 oscillate without striking the middle brace D . Inclined stops B^4 on the wing-frames B , contiguous to the outer ends of the wings B^2 , serve to prevent undue spreading of the ends of the wings. The edges of the wings en- 65 gage with the partitions B^3 to limit the lateral spread of the wings. In order to insure the

spreading of the wings at the proper moment and to make their action certain and effective, I provide means, which I will now describe, for effecting initial partial spreading 70 of the wings.

A series of fingers or lugs a^2 are secured to and project downwardly from the brace-wheels A . The lugs a^2 correspond in number with the pairs of wings, and one lug is situated 75 directly over each pair of wings. The pair of transverse members b^5 of the wing-skeleton contiguous to the middle brace D (which lies directly under the brace-wheel A) have upwardly-inclined extensions b^9 , which cross 80 each other, as shown in Figs. 5 and 6. When the wing-frames are reciprocated, as herein-after explained, the extensions b^9 approach the lugs a^2 as the frame moves upward, and at the instant before the frame reaches the 85 limit of its upward movement the extensions engage with the lugs and the lugs act on the extensions to spread the extensions, so as to produce such initial spreading of the wings before they start downward as to insure full 90 and complete spreading of the wings at the instant of the beginning of the downward movement of the wing-frame, thus assuring effective action of the wings during the whole downward movement of the frame. When 95 the frame reverses its movement and begins to again move upward, the wings gravitate to an approximately vertical position and do not materially impede the upward movement of the frame. When the frame again approaches the limit of its upward movement, the partial spreading of the wings is again automatically effected, as above set forth, and thus the wings are alternately expanded and collapsed so long as the operation of the 100 apparatus continues.

From the foregoing description it will be seen that when the wing-frames are rapidly reciprocated the wings will aid in lifting the apparatus. When the apparatus has been 110 thus lifted to the desired altitude, the reciprocating movement of the wing-frames may be suspended. The apparatus will then descend by gravity sufficiently to cause the wings to spread, so that the wing-frames and 115 their spread wings will form aeroplanes, which, in conjunction with any suitable gas-field, will support the apparatus as it floats on or is propelled through the air.

Any suitable means may be employed for 120 reciprocating the wing-frames. I preferably employ a suitable motor E , such as a gas-engine or an electric motor, secured in a central position on the lower wheel A . Double cranks E' , driven by the motor E , are connected with the guides D' by connecting-rods E^2 or equivalent connecting devices, the construction and arrangement of the parts being 125 such that as the cranks rotate they impart oppositely-reciprocating movement to the 130 wing-frames—that is to say, as one wing-frame ascends the other descends. For the

purpose of propelling the apparatus through the air or controlling its movement in the air I employ rotary propellers G, driven by the motor through the instrumentality of mechanism which I will now describe.

There are two propellers, one on each side of the apparatus, arranged to run independently at the same speed or different speeds and arranged so that either or both may run backward or forward and may be started, reversed, or stopped at pleasure. Both of the propeller-driving mechanisms are exactly alike, so a description of one will suffice for both. The driving mechanism is housed in a suitable shell or housing G', which may be supported in any suitable manner in any convenient position on the apparatus. Shafts G², G³, and G⁴ are mounted to turn in bearings g on the shell G'. The propeller G is secured on the outwardly-projecting part of the shaft G². Wheels g', g², and g³ are secured on the shaft G², and similar complementary wheels g⁴, g⁵, and g⁶ are secured on the shaft G³. The wheels g' and g⁴ are adapted to run in frictional contact with each other, and in like manner the wheel g² runs in contact with the wheel g⁵ and the wheel g³ runs in contact with the wheel g⁶. I have shown and described a train of friction-wheels for operating the propellers; but it is obvious that a similar train of cog-wheels may be used for the same purpose without departing from my invention. Grooved pulleys g⁷ and g⁸ are secured on the shaft G³. Grooved pulleys g⁹ and g¹⁰ are loose on the shaft G⁴ when not engaged by the clutch member g¹². The clutch member g¹² turns with and is slidable on the shaft G⁴ and may be shifted to the right or the left by means of the lever G⁵. On the hubs of the pulleys g⁹ and g¹⁰ are clutch members (not shown) adapted to be engaged by the clutch member g¹². By sliding the member g¹² to the right it will engage with and bring into action the pulley g¹⁰. By sliding it to the left it will engage the pulley g⁹, and by leaving it midway between the pulleys, as shown in Fig. 10, both of the pulleys will be disengaged and the shaft G⁴ will run idle. Belts g¹³ run on the grooved pulleys. One of the belts is straight and the other is crossed, as shown in Fig. 9, so that the shaft G³ may be driven to turn forward or backward, according as the straight belt or the crossed belt is used. A pulley G⁶, fixed on the motor-shaft, carries a belt g¹⁵, which runs on the pulley g¹⁴ and drives the shaft G⁴. The wheels g', g², and g³ are all of different diameters and run in frictional contact with the wheels g⁴ and g⁵ and g⁶, respectively. The wheels being of different diameters, the speed of the propeller may be changed by sliding the wheels g', g², and g³ to the right or left on the shaft G², so as to cause circumferential contact of the pair of wheels adapted to produce the required speed. A lever G⁷, fulcrumed on the shell and having a fork fitting in a circumferential groove in the hub

of the wheels, serves to shift the friction-wheels to the right or the left, as occasion may require.

A sail H is detachably connected with the mast A² in a vertical position parallel to the mast and transversely perpendicular to the axis of the propellers. The sail H serves to steady the motion of the apparatus in the same manner that the keel of a ship steadies the motion of the vessel. When it is desired to travel with the wind, the propellers may be operated to turn the apparatus so as to present the sail broadside to the wind. In like manner the apparatus may be turned to present the edge of the sail to the wind or to hold the sail at any desired angle to the wind as may be found expedient in navigating the apparatus.

As a means to prevent injury to the apparatus by striking fixed objects or the ground while descending or landing I provide at the lower ends of the posts A' inflated elastic balls J, which when they strike any fixed object will yield and break the shock, so as to prevent injury to the apparatus.

The diameter of the brace-wheels A is preferably one-half of the diameter of the wing-frames B, and the middle braces D of the wing-frames are of the same diameter as the brace-wheels and carry the guides D', which slide on the posts A'.

By employing this construction and arrangement of the parts I am enabled to give intermediate support to the wing-frames, and also to prevent rotary movement of the wing-frames on the mast A², and also to guide and steady the reciprocating movement of the wing-frames. These features are of great practical advantage in employing circular wing-frames, for the reason that wing-frames of that form permit the use of wings radiating from a common center and supported at both ends in such manner as to distribute the stresses equally over the whole frame and for the further reason that the rims of the wing-frames bind together all the parts of the frame in such manner that such twisting of the frame as might cause binding of the wings is practically impossible. Another practical advantage of the circular wing-frames is that in turning the apparatus, so as to give the sail any desired direction with respect to the wind, they present relatively less superficial area subject to the direct action of opposing air-currents than would be presented by wing-frames of rectangular or other polygonal form and facilitate instead of retarding the rotation of the apparatus in the air. The circumferential surface of the wing-frames may be compared to the circumferential surface of a revoluble shaft, the air being the support or medium in which the shaft turns. When the apparatus is headed against the wind, the radially-disposed wings receive air-pressure alike on both sides of the directional line of travel of the apparatus and centralize the air-pressures, so that the

greatest strains are directed against and borne by the strongest parts—viz., the middle braces D, the mast A², and the posts A'.

I am aware that oppositely-reciprocating wing-frames have long been used. I therefore do not broadly claim that feature.

Having fully described my invention, what I claim as new, and desire to secure by Letters Patent, is—

10. 1. In an apparatus of the class described, the combination of a circular wing-frame, radiating partitions dividing said wing-frame into sections, inclined stops at the outer ends of said sections and wings mounted in said

15 sections and engaging with said partitions and stops to limit the spread of said wings as set forth.

2. In an apparatus of the class described, the combination of a main structure, wing-frames, means for reciprocating said wing-frames, wings mounted on said wing-frames and means for initial spreading of said wings, as set forth.

3. A wing-frame for apparatus of the class described, consisting of a central hub, circu-

lar rims, spokes radial to said hub, removable wing-supports above and parallel to said spokes and radial partitions between said spokes; in combination with wings mounted on said wing-supports, as set forth.

4. In an apparatus of the class described, the combination of vertical posts, brace-wheels secured to and connecting said posts, guides slideable on said posts, circular wing-frames to which said guides are secured, radially-disposed wings mounted on said wing-frames, cross-pieces connecting said guides, a motor mounted on one of said brace-wheels, double-crank shafts driven by said motor, and connecting-rods connecting the cranks of 35 said crank-shaft with said guides respectively as set forth.

In witness whereof I have hereunto subscribed my name, at Springfield, Illinois, this 30th day of June, 1902.

CHARLES E. VAN DEVENTER.
